UNITED STATES PATENT OFFICE

1,946,329

PROCESS OF CRACKING MINERAL OIL

Arthur E. Pew, Jr., Bryn Mawr, Pa., assignor to
 Sun Oil Company, of Philadelphia, Pa., a cor-
 poration of New Jersey

Application November 9, 1929. Serial No. 405,870

8 Claims. (Cl. 196—61)

In order to crack, in the vapor phase, crude oil or any product, such as gas oil, resulting from the distillation of crude oil, in order to produce comparatively low boiling products such as gasoline, such oil as is passed through the vapor phase cracking zone should not only be completely vaporized, but it is important that the vapor should be perfectly dry. An oil may be so completely vaporized that no entrained liquid may be separated therefrom by any mechanical device for throwing out any entrained liquid, but it may still contain sufficient very finely divided particles or very moist vapors that are practically at the dew point, in consequence of which, when the vapors are exposed to moderately high temperatures, there is a decided formation of carbon on the metal surface through which the heat is conducted to the vapors. The amount of carbon so formed is relatively very small, but it builds up on the metal walls and in time so reduces or obstructs the flow that it is necessary to shut down the equipment for cleaning.

It is, of course, obvious that one method of overcoming this difficulty is to superheat or raise the temperature of the vapors so that they are completely dried and free of any moisture or finely divided entrainment. This method has been used for this purpose with proper distribution of heating surface. In a very mild form of heating this can be done with a reasonable degree of success. When, however, the drying of the vapors is effected in this way, the lack of uniform conditions, which it is almost impossible to maintain, militates against success. Any excessive temperature in the drying zone causes accumulation of carbon in a relatively short period, while any drop in temperature in the drying zone which does not fully dry the vapors, even for relatively short periods, allows the moist vapors to go into the cracking zone and thus form carbon very rapidly in the cracking tubes. Another cause of trouble with such an arrangement is that the carrying over of any actual liquid into the drying zone causes the formation of vapors in the drying zone, which then are saturated or even carry entrained liquid, thus introducing such saturated vapor or entrained liquid into the cracking tubes.

The process involving the present invention is intended and adapted to overcome these difficulties and to provide more positive means of completely drying the vapors before they are introduced into the vapor phase cracking zone. It involves the practice of a number of steps including the introduction, in limited proportion, of a dry gas which, preferably, is heated to about the same temperature as the vapors to be cracked, and which is not relied upon to impart to the vapors the heat, or any part thereof, required for cracking.

The entire process will first be described and

the invention will then be particularly pointed out in the claims.

The charging stock (preferably gas oil) is taken from the tank through line 1 and pump 2 through heat exchangers 3 and 150 into the pipe 65 still 4, where it is heated up to practically completely vaporize the oil as it enters the vaporizer 5. The preferred pressure set up by pump 2 is such that the outlet pressure on the pipe still 4 is maintained at from 50 to 100 pounds, which is 70 simply the back pressure of the vapor phase cracking and fractionating equipment. The vapors leave the top of vaporizer 5 and pass through a separator 6, which takes out any mechanical entrainment of liquid and prevents any 75 liquid passing beyond this part of the line. From separator 6 the vapors go to a gas and vapor mixer 8, where a dry gas is introduced which has been heated, preferably, to about the same temperature as the vapor. Here the dry gas and oil 80 vapors are thoroughly mixed. The mixture then passes into the vapor phase cracking coil 9, is raised therein to the required or desired temperature (say about 950° F. or above) and passes out at 10 into the spray cooler tower 11, where it is 85 cooled and partially separated. In tower 11 the heavier portion is drawn off at the bottom through outlet 12 and the remainder goes out as vapor through line 13 and into fractionating tower 16, where the lighter portions are separated. Gasoline and gas go out through line 17, 90 through a clay tower 23 and through a condenser 24 into a gas separator 30, from which gasoline is taken out through line 31. The gas escapes through line 32 into an absorption tower 33 and the stripped gas is passed out through lines 34 and line 40 to a gas holder, or to the atmosphere; or the gas, or a portion thereof, may pass to line 36.

From tower 16 an intermediate product is 100 taken out through line 19 and, after passing the heat exchanger 3 and/or other coolers, goes to storage; or it may be used again in the process by being conducted through by-pass line 190 to the feed or charging stock line; the product being very similar to the original gas oil which is used as charging stock.

All of the gasoline vapors and gas are not taken out of tower 16 through line 17, but a regulable proportion is taken out through line 18 and passed through condenser 26 into tank 27; the condensate being taken through pump 28 and line 22 back into the top of the fractionating tower. This condensate is used for controlling the temperatures at the top of the tower in order to fix the maximum boiling point of the product taken through line 17. Line 29 is the vent which vents the gas from tank 27 so as to maintain the proper level of liquid in this tank.

The condensate in tower 16 is conducted back 120

to the upper part of tower 11, where it promotes or effects the cooling and fractionation of the cracked vapors from the cracking coil 9 and controls the outlet temperature through line 13. 5 This condensate is conveyed to tower 11 through lines 20 and 15, being cooled by heat exchange, at 150, with incoming charging stock. The line 10 50, which leads from the outlet at the bottom of vaporizer 5, is for conveying away any heavy ends which may not be completely vaporized when the oil leaves the pipe still. This high boiling product may be carried back into line 15, as shown, or may be withdrawn from the system. If a relatively heavy charging stock, such as a 15 topped crude, is used, then a considerable portion is drawn off at the bottom of vaporizer 5 and this should then be passed through line 14 into tower 11. Such heavy portions are exposed to the highest 20 temperature in tower 11 and in this way cracked to some extent and the heavy portions are drawn off through line 12 along with the heavy products from the vapor phase cracking coil.

As hereinbefore stated, the gas which is combined with the vapor at 8 may be taken from the 25 dry gas line 34 of the plant or, through line 41, from any other source. It may go through line 36 and be heated partially by heat exchange at 360 with the oil from tower 16 and partially by tubes 37 which are provided in the pipe still or 30 cracking furnace. This gas is thereby raised, preferably, to the same temperature as the vapor, or approximately 750°. This gas, when heated to the same temperature as the oil vapor, contains considerable superheat, or, in other words, 35 it is heated above the saturation point for this pressure. When such gas is combined with the saturated vapors it dries the vapors, although it does not raise the temperature of the mixture above that of either the vapors or the gas previous to their combination. This mixture of 40 saturated vapor with the superheated gas has the effect of reducing the dew point of the mixture so that no form of moisture can exist at this temperature. The greater the amount of the 45 superheated gas which is used, the lower will become the dew point of the mixture. The ratio of such gas, by weight, to the oil vapor, is preferably from 5 to 15%. This percentage of gas effectively maintains the vapors in a perfectly dry state, so 50 that when the mixture is introduced into the cracking coil at 9 it withstands the high temperature heating surface without any substantial carbon formation. The percentage of gas, by weight, may, under exceptional conditions, be 55 as low as 1% or higher than 15%. An excessive volume of gas may not affect operativeness, but would be open to serious objections.

The drying of the oil vapors may also be effected by combining the process herein described 60 of mixing dry gas therewith with a reduction of pressure between the vaporizer and the cracking coil, as set forth in an application, Serial No. 405,811, filed of even date herewith.

Having now fully described my invention, what 65 I claim and desire to protect by Letters Patent is:

1. The process of cracking mineral oil charging stock which comprises vaporizing the oil in one locus, removing from the vapors mechanically entrained liquid particles, then drying the oil vapors in another locus by mixing therewith a relatively small proportion of a dry hydrocarbon gas, then at still another locus heating the mixture to a cracking temperature and cracking the oil vapors, and cooling and fractionating the vapors.

2. The process of cracking mineral oil charging stock which comprises vaporizing the oil in one locus, removing from the vapors mechanically entrained liquid particles, then drying the oil vapors in another locus by mixing therewith a relatively small proportion of a dry hydrocarbon gas at a temperature close to but not substantially exceeding that of the oil vapors, then at still another locus heating the mixture to a cracking temperature and cracking the oil vapors, and cooling and fractionating the vapors. 80

3. The process of cracking a mineral oil charging stock which comprises vaporizing the oil in one locus, removing from the vapors mechanically entrained liquid particles, then drying the oil vapors in another locus by mixing therewith a relatively small proportion of a dry gas, then at still another locus heating the mixture to a cracking temperature and cracking the oil vapors, and cooling and fractionating the vapors. 85

4. The process of cracking a mineral oil charging stock which comprises vaporizing the oil, allowing the vapors to expand and removing heavy fractions and mechanically entrained liquid particles, then drying the oil vapors by mixing therewith a relatively small proportion of a dry gas, then heating the mixture to a cracking temperature and cracking the oil vapors, and then cooling and fractionating the vapors. 90

5. The process of cracking a mineral oil charging stock which comprises vaporizing the oil in one locus, removing from the vapors mechanically entrained liquid particles, then drying the oil vapors in another locus by mixing therewith a substantial proportion of dry gas less than about 15%, by weight, of the vapors, then at still another locus heating the mixture to a cracking temperature and cracking the oil vapors, and cooling and fractionating the vapors. 105

6. The process of cracking a mineral oil charging stock which comprises vaporizing the oil in one locus, removing from the vapors mechanically entrained liquid particles, then drying the oil vapors in another locus by mixing therewith a relatively small proportion of a dry gas at a temperature close to but not substantially exceeding that of the vapors, then at still another locus heating the mixture to a cracking temperature and cracking the oil vapors, and cooling and fractionating the vapors. 115

7. The process of cracking a mineral oil charging stock which comprises vaporizing the oil in one locus, removing from the vapors mechanically entrained liquid particles, then drying the oil vapors in another locus by mixing therewith a relatively small proportion of a dry gas at a temperature about that of the vapors, then at still another locus heating the mixture to a cracking temperature and cracking the oil vapors, and cooling and fractionating the vapors. 130

8. The process of cracking a mineral oil charging stock which comprises vaporizing the oil in one locus, removing from the vapors mechanically entrained liquid particles, then drying the oil vapors in another locus by mixing therewith a substantial percentage of a dry gas less than about 15%, by weight, of the vapors and a temperature close to and not substantially exceeding the temperature of the vapors, then at still another locus heating the mixture to a cracking temperature and cracking the oil vapors, and cooling and fractionating the vapors. 140
